UNITED STATES PATENT OFFICE

124,427

DESIGN FOR A SIDE OF A CRIB OR BASSINET

Abraham G. Feldman, Chicago, Ill.

Application April 29, 1940, Serial No. 92,029

Term of patent 3½ years

To all whom it may concern:

Be it known that I, Abraham G. Feldman, a citizen of the United States, residing at Chicago, in the county of Cook and State of Illinois, have invented a new, original, and ornamental Design for a Side of a Crib or Bassinet, of which the following is a specification, reference being had to the accompanying drawing, forming part thereof.

Fig. 1 is a front elevational view of a side of a crib or bassinet, showing my new design;

Fig. 2 is an end elevational view; and

Fig. 3 is a magnified section taken on the line 3—3 of Fig. 1.

I claim:

The ornamental design for a side of a crib or bassinet, as shown.

ABRAHAM G. FELDMAN.
